G. S. LEWIS

APRON HOLDER

Filed May 10, 1927

UNITED STATES PATENT OFFICE.

GEORGE S. LEWIS, OF SPRINGFIELD, MASSACHUSETTS, ASSIGNOR, BY MESNE ASSIGNMENTS, TO AUTO SMOCK AND CLAMP COMPANY, OF SPRINGFIELD, MASSACHUSETTS, A CORPORATION OF MASSACHUSETTS.

APRON HOLDER.

Application filed May 10, 1927. Serial No. 190,300.

This invention relates to an apron holder, particularly useful in connection with automobile repair work. In my co-pending application Serial No. 187,688, filed April 29, 5 1927, I have shown an apron holder for the same general purpose. The present invention is for the special purpose of fastening the apron on the backs of the front seats. From this holding position the apron of 10 paper for example, may be draped over the seats to protect them from the mechanic's dirt as he works in the car. Most of the repair work within the body of an automobile requires the mechanic to work in the 15 front seats or forwardly thereof.

According to the idea of this invention, the structure is particularly worked out to provide an apron holder of exceptional convenience for manipulation by the mechanic 20 and one of exceptional utility for holding an ordinary sheet of paper, for example, to cover the upholstery of the front seats of automobiles as an apron, against which mechanics may lean when inside the car 25 body, and without soiling the upholstery.

The features of invention involved will be understood best from the following description of the accompanying drawings and from the annexed claims.

30 In the drawings—

Fig. 1 shows the holder in position against the back of the front seat of an automobile with the paper apron spread out over the rear side, the top, the front side, and the 35 bottom of the front seat of an automobile;

Fig. 2 is a side detail view of the adjacent portions of the holder, shown separated and arranged to overlap; and

Fig. 3 is a detail plan view of the portions 40 shown in Fig. 2 but in overlapped position.

Fig. 4 is a modified form of my invention showing a detail side view of the overlapping portions of the clamp in spaced positions.

45 In the use of the invention a garage mechanic before starting his work within a closed automobile body, procures an ordinary sheet of paper 1 for an apron, which need not be of any special shape so long as it is large enough. He spreads this apron 1 over the upholstery of the seat up and over the back, so that it extends down the back 50 at the rear as well as the front for the holder

to get a good grip in the clamping operation which will be described.

On the front side of the seat back 10 one places the front portion 3 of the holder. This portion is preferably of flat, comparatively narrow, rather stiff spring metal, and generally follows the contour of the upholstered back against which it is to press. Then the rear portion 4 is placed on the rear side of the seat, preferably as shown. The adjacent ends 5 and 6 of portions 3 and 4 are put in overlapping position by inserting end 5 under end 6, passing it through the rectangular slot 7 in end 6 so as to place part of end 5 on the bottom side and part on the top side of end 6, so that there may be a real binding action between portions 3 and 4 at their overlapping ends whenever there is a tendency for the downwardly extending parts of such portions to separate. The overlapping ends 5 and 6 are locked 60 against a longitudinal slipping and separating movement by the engagement of the headed stud 7 on end 6 with one of the hooks or transverse slots 8 provided in the edge of end 5. This arrangement makes an adjustable locking connection between the overlapping ends 5 and 6.

The rear portion 4 is preferably made up of an outwardly extending upper horizontal part 20, a downward bend 21, a vertical part 22, an inward bend 23, an inwardly extending horizontal part 24, a downward bend 25, a lower vertical seat contact part 26, the lower end of which is bent outwardly as at 27. This arrangement provides for an outward extension of portion 4 (comprising parts 20 and 22) and an inward extension (comprising parts 24 and 26) with relation to the seat back 10 and clamping portion 3. By such an arrangement the portion 4 provides for the clamp as a whole, a bow shaped spring portion which provides for portion 3 lying closely adjacent and for the most part contacting the front contour of the seat where it is of advantage. The rear portion 4 of the clamp, therefore, is positioned and shaped quite differently than the front portion 3. This is so in order for each to cooperate best with the other in the joint function of holding the paper apron on the seat. The rear portion provides for a very 100 large spring action; by its outward and in-

ward extensions it passes around a coat or rug rail that may be on the back of the seat. The contacting part 26 bears against the seat back in line with a good contacting part of portion 3. Since the paper apron has a bight hold over the back of the seat, it is held for a considerable length by the spring pressed portion 3, and the rear portion 4 may be shaped as described for contributing features to the holder which would not be present, if both portions 3 and 4 were shaped alike.

Due to the particular arrangement shown, the spring portion 3 has a fulcrum for bending purposes at the overlapping end 6 of portion 4 in front of the slot. From this fulcrum the resiliency of portion 3 increases as the lower end is approached. The lower part, beginning at about the level with the reverse bend at the lower end of portion 4 is the part that can be pressed resiliently against the paper apron and against the seat with the greatest force for apron holding purposes. Furthermore, as the apron is pressed against the seat, the springs of the upholstery in the seat back are put under strain to press outwardly against portion 3. Consequently the paper apron 1 is held against the front side of the seat back with spring pressure on both sides and over sufficient area to retard slipping. In addition, the apron is preferably bent over the top of the seat back and downwardly, so as to be engaged effectively with the reverse bend of portion 4 at the bottom. With this arrangement, the apron is held most effectively by a spring clamping action and with a bight over the seat back to help retard slipping action.

The portion 4 as shown, is preferably of heavier gauge metal stock than portion 3 and although resilient, is quite a bit stiffer in every respect than portion 3. Thus portion 4 is the "backbone" of the holder, or its principal supporting element, while the portion 3 is the more active spring holding element of the holder. By working out the structure in this manner, the portions cooperate better for their purpose than if they were equal spring portions. The nature of the contacting conditions of portion 3 permits the best result by increased resiliency as compared with portion 4, and this increased resiliency can be best accomplished by making portion 4 stiffer and supporting portion 3 from it.

The simplicity of manufacture, but more particularly the ease of manipulation by the user should be noted. When the apron is placed over the seat, the portion 4 is placed in position, portion 3 is inserted or threaded through the hole near the end, as shown in Fig. 3, and hooked in overlapping position on the stud just about as easily as a hook is put through an eye. The holder is then

pressed downwardly against the paper and seat from the top into the position shown in Fig. 1, and the lower ends of portions 3 and 4 are set with an effective spring clamping action.

Ordinarily, two holders—one at each side of each seat if there are two front seats, should be used, but it is quite possible to use one for each seat by placing it about at the middle. In any event the holder itself need not come in contact with any part of the seat or its upholstery because the paper apron lies between the holder and the upholstery for protection purposes with regard to the holder just as it does with regard to the mechanic's greasy clothes.

Therefore, a clean piece of paper of suitable area and regardless of shape, may be used as the temporary seat cover or apron in garages and whether or not the apron holders are soiled, the upholstery of the automobile will be protected.

By this invention the repeated use of special seat covers in garage work is avoided and no special provision need be made for keeping the apron holder clean because no part of it need touch the automobile directly. The nature of the invention is such that the mechanic should find it more convenient to fasten the apron in place with the holder and drape the seat, than to try to drape the seat without the use of the holder. In prior practice, even when special protecting seat covers are provided in garages, the mechanics frequently grab a piece of wrapping paper to use as a loose seat apron rather than fit the temporary covers specially bought for protection purposes. With the holder herein described, the mechanic is helped in arranging his piece of wrapping or other paper for apron purposes and he can cover the seat decently and fix the paper in position without any real effort on his part.

In Fig. 4 I have shown a modified form of my invention planned for use on bucket seats found, for example, in Ford cars of the closed type. These seat backs have little upholstery and are relatively narrow from front to rear. According to the modification, the portion 3' is made like the portion 3 of Fig. 1, but the portion 4' is formed to slope toward the seat back and is provided with an end portion bent upwardly to contact with the seat back as indicated. Thus portion 4' is arch shaped, but instead of the contacting foot at the bottom extending downwardly, it extends upwardly. This upwardly extending contacting foot is planned to follow the contour of the back of the seat which is substantially flat. On these narrow seats it may be desirable to have the slotted end portion 6' bent backwardly on itself, with the bend at about the middle of the rectangular slot, so that the overlapped part of portion 3' may pass through the slot

and bind between the parallel spaced end parts of portion 4' at end 6'. This is all shown in Fig. 4.

The forms of the invention as specifically shown and described, may obviously be varied and changed into other forms without losing the idea of the means to carry out the invention as exemplified in this specification and particularly pointed out in the 10 claims.

I claim:

1. A temporary apron holder for an automobile seat or the like, comprising two 15 spring holding members of curved flat spring metal, a rectangular transverse slot near the end of one member slightly wider than the width of the other member to permit overlapping of the adjacent end of the other member on opposite faces of the slotted 20 member, a stud on the slotted member spaced rearwardly from the slot and about in line with one side thereof, a series of transverse slots in the edge of the other member which are adapted to engage the stud, all arranged 25 so as to bind the overlapped ends together whenever their free ends bend to separate

and to permit adjustment of the holding members at their overlapped portions.

2. A temporary apron holder for an automobile seat or the like, comprising a long, 30 comparatively narrow, flat spring metal portion formed to follow the approximate contour of the front side of a seat back and having an upper end provided at the edge thereof with a series of transverse slots, a second 35 member of relatively more rigid flat strap metal having an upper portion adapted to overlap the said slotted portion of the other member and provided near its ends with an upwardly offset portion and provided with 40 a rectangular slot to receive said slotted portion so that the latter may overlap the rigid portion on opposite sides thereof and a stud on the rigid portion whereby it may have its overlapping portion adjustable by the engagement of said slots with said stud, said 45 latter portion extending downwardly and being bent into arched shaped form and into a contacting foot at the lower end thereof.

In testimony whereof I have affixed my 50 signature.

GEORGE S. LEWIS.
